UNITED STATES PATENT OFFICE.

CHARLES A. SINGER, OF ST. LOUIS, MISSOURI, ASSIGNOR TO SINGER AUTO TRAFFIC SIGNAL COMPANY, OF ST. LOUIS, MISSOURI, A CORPORATION OF DELAWARE.

MULTIPLE SWITCH.

1,239,833.

Specification of Letters Patent. Patented Sept. 11, 1917.

Application filed May 11, 1916. Serial No. 96,865.

To all whom it may concern:

Be it known that I, CHARLES A. SINGER, a citizen of the United States, residing at St. Louis, Missouri, have invented a certain 5 new and useful Improvement in Multiple Switches, of which the following is a full, clear, and exact description, such as will enable others skilled in the art to which it appertains to make and use the same.

10 This invention relates to multiple switches, and has for its main object to provide a compact multiple switch of novel construction that is equipped with an efficient means for governing the operation of 15 the controlling elements of the switch.

Another object of my invention is to provide a multiple switch that comprises a plurality of controlling elements, a locking means constructed in such a manner that 20 after one controlling element has been rendered operative, said means prevents any one of the other controlling elements from being rendered operative at the same time, and a device that is adapted to be operated 25 so as to restore the operative controlling element to its normal position and also to render said locking means inoperative. Other objects and desirable features of my invention will be hereinafter pointed out.

30 Figure 1 of the drawings is a top plan view, partly broken away, of a multiple switch constructed in accordance with my invention.

Fig. 2 is a vertical cross-sectional view of 35 said switch.

Fig. 3 is a horizontal sectional view, taken on the line 3—3 of Fig. 2.

Fig. 4 is a bottom plan view of the switch.

Fig. 5 is a perspective view of the center 40 push button and the locking device controlled by same.

Fig. 6 is a perspective view of one of the switch levers; and

Fig. 7 is a detail top plan view of one of 45 the switch levers, illustrating the means used for holding said lever in its operative and inoperative positions.

Referring to the drawings, which illustrate a switch constructed in accordance 50 with my invention that is particularly designed for use on an automobile for governing the operation of a traffic-signaling device provided with indicators or signals that are electrically-operated, A designates a

housing member, preferably of cylindrical 55 form, which is provided at its upper end with a top plate 1 in which the controlling elements of the switch are mounted. The switch herein shown is provided with four selective controlling elements, each of which 60 governs an independent electric circuit, such, for example, as circuits in which independently-operated signals are arranged. If desired, the switch may be provided with two additional controlling elements, one for 65 governing the horn circuit of an automobile, and the other for governing the light circuit of the automobile. I wish it to be understood, however, that my invention is not limited to a multiple switch adapted for 70 use on an automobile for controlling the circuits of an electrically-operated signaling device, nor is my broad idea limited to a switch provided with selective controlling elements and also additional controlling 75 elements for governing independent circuits.

The selective controlling elements of the switch preferably consist of four push buttons B, each of which is operatively connected to a switch lever C, or other suitable 80 form of electrical connector that co-operates with a contact 2 to which one wire α of an electric circuit leads, as shown in Fig. 3, the switch lever C being provided at its outer end with a portion 2^a that engages its co-operating contact when the push button B to which the switch lever is connected is depressed. The push buttons B are slidably mounted in the top plate 1 of the switch housing, and each push button is provided 85 with a depending arm 3 that is pivotally connected to the switch lever with which the push button co-operates, the lower end of the arm 3 preferably passing through a hole 3^a in the switch lever and being upset 90 so as to simplify the construction of the switch and reduce the cost of manufacturing same. The push buttons B are arranged concentric with relation to the center axis of the switch housing, as shown in Fig. 1, and 100 the switch levers C are arranged at right angles to each other and in such a manner that the inner ends of said levers will terminate at approximately the center of the switch housing. At the center of the switch housing are four vertically-disposed posts 5 on which the switch levers C are pivotally mounted, said posts being so arranged that 105

they will form a guideway for a locking member D that coöperates with said switch levers to lock three of them in an inoperative position when the fourth switch lever is rendered operative. The locking device D herein shown consists of a block that is arranged to reciprocate longitudinally of the center axis of the housing of the switch, and said locking device is secured in any suitable manner to a resetting element, preferably a push button B' that is arranged at the center of the top plate 1 of the switch housing and which is adapted to be depressed so as to restore the push button B that is operative and also move the locking device D into an inoperative position. The resetting element B' is provided at its lower end with a flange or bearing portion 6 which is so arranged with relation to the switch levers C that it lies above the inner end portions of all of said switch levers. The locking device D is connected to the lower end of a spindle 7 that projects downwardly from the resetting element B', and said locking device is provided with four notches 8, as shown in Fig. 5, that coöperate with depending arms 9 on the switch levers C to lock certain of said switch levers in an inoperative position under certain conditions. When all of the controlling elements B are inoperative, or in their raised position, the locking device D will be positioned below the depending arms 9 on the switch levers out of the path of movement of said arms. When one of the controlling elements B is depressed, or rendered operative, the inner end portion of the switch lever C connected to said controlling element will strike the flange 6 on the resetting element B' and move said resetting element upwardly into the position shown in Fig. 2, the upward movement of said resetting element causing the locking device D to move upwardly into position to engage or coöperate with the depending arms 9 on the switch levers of the three inoperative controlling elements B, and thus preventing any of said inoperative controlling elements from being depressed or rendered operative. To restore the operative controlling element B it is necessary to first depress the resetting element B', so as to exert downward pressure on the inner end portion of the switch lever connected to said operative controlling element, and thus move the outer end portion of said switch lever upwardly out of engagement with its coöperative contact 2, the downward movement of the resetting element B' causing the locking device D to move into its inoperative position. It will thus be seen that when one of the four circuits governed by the controlling elements B is closed, it is impossible to close any of the other circuits without first opening the closed circuit, the act of opening the closed

circuit also causing the locking mechanism of the switch to be rendered inoperative. Consequently, such a switch is particularly adapted for use in a signaling apparatus provided with independently-operated signals, only one of which is intended to be operative at the same time, on account of the fact that the switch is so constructed that it is impossible for it to be operated in such a manner that one signal will be rendered operative, and thereafter another signal will be rendered operative while the first signal remains operative.

It is immaterial, so far as my broad idea is concerned, how the coöperating parts of the switch are mounted and insulated from each other, but I prefer to mount the cylindrical housing A of the switch, which is formed of metal, on two disk-shaped pieces of insulating material 10 and 11 arranged inside of said housing at the lower end of same and secured to same by means of bolts or screws 12 that pass through the plates 10 and 11 and through inwardly-projecting ears 13 on the housing A, as shown in Fig. 2, a spacer 14 being arranged between the plates 10 and 11, so as to provide a space for receiving other switch members that control independent circuits, as hereinafter described. The four center posts 5 are mounted on the insulating plate 10 and are securely connected thereto by screws or other suitable fastening devices, and a disk-shaped piece of insulating material 15 is connected to the upper ends of said posts in such a manner that it will lap over the upper edge of the cylindrical-shaped member that forms the side wall of the housing A. The top plate 1 of the switch housing, which is formed of metal, is held in position by means of the screws that connect the top insulating member 15 to the posts 5.

Two switch members or electrical connectors 16 and 17 that are arranged in the space between the insulating members 10 and 11 control independent circuits separate and distinct from those governed by the controlling elements B, as shown in Fig. 3, the switch member 16 preferably consisting of a spring contact that is operated by a push button 16^a slidably mounted in the insulating member 11, and the switch member 17 consisting of a pivotally mounted lever provided with a finger piece 17^a that projects downwardly through an arc-shaped slot in the insulating member 11. The switch member 17 is carried by a plate that is provided with a binding post 17^b, and the switch member 16 is connected to a binding post 16^b. Both of said switch members 16 and 17 coöperate with a contact plate 18 arranged on the underside of the insulator 10 and provided with a binding post 18^b to which a conductor leads, the contact plate 18 being arranged in such a position that the

spring contact 16 will engage same when the push button 16^a is depressed, and said plate being provided at one end with a contact 18^b which the switch member 17 engages 5 when said member is moved into its operative position. By constructing the switch in this manner I can use one wire to form one side of each of the circuits governed by the two switch members 16 and 17 and 10 by the four controlling elements B, in view of the fact that the contact plate 18 is electrically connected to two of the center posts 5, and all four center posts are electrically connected together by the metal top plate 1 15 of the switch housing.

If desired, the switch may be provided with means for holding the switch levers C in both their operative and inoperative positions, so as to prevent them from moving 20 accidentally out of the position to which they have been moved, one means that I have found to be very efficient for this purpose consisting of spring-pressed balls 19 mounted in the center posts 5 and coöperating 25 with holes or depressions 20 formed in the side faces of the switch levers C. When one of the switch levers C is in an operative position the ball 19 in the post on which said lever is mounted will enter one of the 30 holes 20 in said lever, and thus hold it in position, and when said lever is restored to its inoperative position, said ball 19 will enter the other hole 20 in the lever, and thus yieldingly lock it in position.

35 A multiple switch of the construction above described is compact; it can be manufactured cheaply, and it is so constructed that it is impossible for a controlling element to be rendered operative while a previously actuated controlling element is in an operative condition.

Having thus described my invention, what I claim, and desire to secure by Letters Patent, is:

45 1. A multiple switch provided with a plurality of independently-operable selective controlling elements grouped about a central point, a locking device arranged at said central point and common to all of the controlling elements for locking the inoperative controlling elements when one of said controlling elements is rendered operative, and means for rendering said locking device inoperative with respect to all of the controlling elements when the operative controlling element is restored to its inoperative position.

2. A multiple switch provided with a plurality of independently-operable selective 60 controlling elements, a device that locks all of the inoperative controlling elements and prevents them from being operated when one of said elements is operative, and a resetting or restoring device, which, upon being operated, restores the operative con-

trolling element and also renders said locking device inoperative.

3. A multiple switch, comprising a plurality of independently-operable selective controlling elements, a resetting device common to all of said controlling elements and arranged so that it will move in one direction whenever any one of said controlling elements is rendered operative, and a locking device governed by the resetting device and 70 arranged so that it will lock the inoperative controlling elements when a controlling element is rendered operative.

4. A multiple switch provided with a plurality of independently-operable selective 80 controlling elements, a resetting or restoring device for said elements, means combined with said controlling elements and said resetting device for causing said device to move in one direction when any one of said 85 controlling elements is rendered operative and for causing the operative controlling element to be restored to its inoperative position when said resetting device is moved in the opposite direction, and means coöperating 90 with said resetting device for preventing the inoperative controlling devices from being operated.

5. A multiple switch provided with a plurality of movable electrical connectors arranged in a group, a locking device that is moved automatically into position to lock all of the inoperative connectors when one of the connectors is rendered operative, and a restoring device common to all of said 95 connectors that controls said locking device.

6. A multiple switch provided with a plurality of switch levers arranged at an angle to each other and in such a manner that the free ends of same are in proximity to each other and grouped about a central point, and a locking device arranged at said central point and combined with said levers in such a manner that when one lever is actuated 105 said device will move automatically into position to lock the other levers.

7. A multiple switch provided with a plurality of switch levers arranged at an angle to each other and in such a manner that the free ends of same are in proximity to each other, a locking device combined with said levers in such a manner that when one lever is actuated said device will move automatically into position to lock the other levers, and a resetting device common to all 115 of said switch levers and operatively connected to said locking device for moving it into an inoperative position when said resetting device is actuated to restore one of said switch levers.

8. A multiple switch provided with a plurality of switch levers arranged at an angle to each other so that the free ends of same are in proximity to each other, posts on which said levers are pivotally mounted, and 120

125

130

a locking device slidably mounted on said posts and adapted to coöperate with said levers in the manner described.

9. A multiple switch provided with a plurality of switch levers arranged at an angle to each other so that the free ends of same are in proximity to each other, posts on which said levers are pivotally mounted, a locking device slidably mounted between said posts and adapted to coöperate with said levers in the manner described, and a resetting device guided by said posts and connected to said locking device.

10. A multiple switch provided with a plurality of switch levers arranged at an angle to each other around a center axis, a locking device that reciprocates longitudinally of said axis, and means for causing said locking device to move into position to engage all of said levers except one when one lever is rendered operative.

11. A multiple switch provided with a plurality of posts arranged in parallel relation to each other, switch levers pivotally mounted on said posts, and a reciprocating locking device slidably mounted on said posts and provided with notches that receive portions on all of said levers except one when said locking device is in its operative

30 position.

12. A multiple switch provided with a plurality of posts arranged in parallel relation to each other, switch levers pivotally mounted on said posts, a reciprocating locking device slidably mounted between said posts and provided with notches that receive portions on all of said levers except one when said locking device is in its operative position, and a resetting device connected to said locking device and arranged in such a position that it can be moved in one direction by the free end of a switch lever that is rendered operative.

13. A multiple switch, comprising a hous-

ing, a plurality of posts arranged in said housing in parallel relation to each other, switch levers pivotally mounted on said posts, push buttons pivotally connected to said levers and projecting through openings in the end wall of the housing, a resetting device having a portion that fits between said posts and which is arranged in the path of movement of the free ends of said switch levers, and a locking plate connected to said resetting device and provided with notches that receive depending arms on said switch levers when said locking plate is in its operative position.

14. A multiple switch, comprising a housing, a plurality of posts arranged in said housing in parallel relation to each other, switch levers pivotally mounted on said posts, push buttons pivotally connected to said levers and projecting through openings in the end wall of the housing, a resetting device having a portion that fits between said posts and which is arranged in the path of movement of the free ends of said switch levers, a locking plate connected to said resetting device and provided with notches that receive depending arms on said switch levers when said locking plate is in its operative position, and spring-pressed detents in said post that coöperate with said switch levers.

15. A multiple switch, comprising a cylindrical-shaped housing member, a plurality of selective controlling elements grouped about the center of said housing, switch levers governed by said controlling elements, a locking device arranged in the center of said housing, means whereby the act of rendering any one of said levers operative causes said device to lock the remaining levers, and means for rendering said locking device inoperative.

CHARLES A. SINGER.
